UNITED STATES PATENT OFFICE.

ROY J. TROUTMAN, OF SHAMOKIN, PENNSYLVANIA.

SANITARY TOILET-SEAT.

1,092,786.

Specification of Letters Patent.

Patented Apr. 7, 1914.

Application filed December 13, 1913. Serial No. 803,629.

To all whom it may concern:

Be it known that I, ROY J. TROUTMAN, a citizen of the United States, residing at Shamokin, in the county of Northumberland and State of Pennsylvania, have invented new and useful Improvements in Sanitary Toilet-Seats, of which the following is a specification.

This invention relates to sanitary toilet seat covers; and it has for its primary object the provision of a device of this character which may be formed principally from a single strip of tissue paper or the like and arranged so that it may be accurately and effectually made to cover all parts of the seat.

Another object of the invention is the provision of a device of this character which will consist of a protecting covering and means adapted to be engaged between the bowl and the seat for securely retaining the cover in an applied position.

A further object of the invention is the provision of holding means for securing the cover in place which will be provided with an extension which may be grasped between the fingers of the hand to facilitate the operation of removing the cover from the seat after use.

With these and other objects in view, the invention consists of certain novel features of construction, combination and arrangement of parts, as will be hereinafter described and claimed.

In the accompanying drawings:—Figure 1 is a top plan view of the cover, showing the application thereof to the seat; Fig. 2 is a perspective view of the cover, showing the manner of initially assembling the covers in package form; Fig. 3 is a section, taken on the line 3—3 of Fig. 1; Fig. 4 is a section taken on the line 4—4 of Fig. 1; Fig. 5 is a perspective view, showing the manner in which the cover may be folded and arranged in a compact package initially; and Fig. 6 is a horizontal section through the front portion of the cover.

The cover is constructed from a main sheet or body 1 of tissue paper, which may be treated, if desired, with an antiseptic solution. The sheet is of a size slightly exceeding the size of the seat to which it is to be applied, and it is provided with a central opening 2 and extending in the direction of the opening are slits 3 by means of which the intervening portions 4 of the sheet between the slits may be flexed or folded in

a downward direction and against the adjacent surfaces of the opening in the seat, as shown in Fig. 4. The outer marginal edges of the sheet are extended slightly beyond the sides of the seat, and are adapted to be folded downwardly in the direction of the bowl of the closet structure, as conventionally illustrated herein. At the sides the sheet is provided with short tabs 5, to which small fastening strips 6 may be cemented or otherwise suitably secured. These strips are provided with relatively free portions 7 that are adapted to be extended into the spaces between the hopper of the bowl and the seat, shown in Fig. 4, and in this manner the cover may be effectually held in an applied position. At the front the sheet is provided with an extension 5' similar to the extensions 5 at the sides of the sheet and as illustrated said extension 5' is provided with a fastening 6' which is identical with the fastener 6 which is adapted to be extended into the space between the seat and the hopper of the bowl structure, as shown in Fig. 3. As an additional protection the sheet is provided at its front with an apron or flap 8 which is normally folded onto the adjacent body of the sheet and which is adapted to be folded to the position shown in Fig. 3, where it will depend slightly into the bowl of the closet structure. The said apron or portion 8 is creased on a longitudinal line, as at 9, so that when it is extended to the position shown in Fig. 3, it will naturally tend to retain such position as will be understood.

At the back the sheet is provided with substantially V-shaped extensions 10, in which perforations 11 are formed. These perforations are adapted to receive sustaining hooks 12 or rods 12 that extend in a horizontal direction from a bracket plate 13. This plate may be secured upon the wall and a number of the sheets may be arranged in package form and they may be singly removed and mounted on the seat as may be required. Owing to the fact that the extensions 5 normally extend beyond the sides of the seat, as clearly shown in Figs. 1 and 4, it is evident that said extensions may be readily grasped between the fingers of the hand and the sheet quickly removed from the seat when desired.

It may be desirable to dispense the sheets from vending apparatus or to otherwise arrange the sheets in individual package form and in view thereof many folds may be taken at appropriate parts of the sheet and

definite portions of the sheet may be inter-folded with each other, so that the cover in its entirety will assume the comparatively compact package shown in Fig. 6.

5 I claim:—

A toilet seat cover comprising a single strip of flexible material provided with a central opening and radial slits extending in the direction of the opening, an apron 10 forming an integral portion of the sheet

and located at the front thereof and normally underlying the adjacent body of the sheet and provided with a longitudinal continuous fold.

In testimony whereof I affix my signature 15 in presence of two witnesses,

ROY J. TROUTMAN.
